UNITED STATES PATENT OFFICE.

ELDRIDGE P. DOUGLASS, OF MARIANNA, ARKANSAS.

EXCAVATOR AND LOADER.

Application filed February 11, 1924. Serial No. 691,943.

To all whom it may concern:

Be it known that I, ELDRIDGE P. DOUGLASS, a citizen of the United States, residing at Marianna, county of Lee, and the State of Arkansas, have invented a certain new and useful Improvement in Excavators and Loaders, of which the following is a full, clear, and exact description, such as will enable anyone skilled in the art to make 10 and use the same.

My invention relates to means especially adapted to be used in connection with a traction engine for the purpose of loading gravel or other excavated material into 15 wagons or other conveyances by which it may be removed from the point at which it is unloaded.

The objects of my invention are to provide a simple and efficient mechanism by 20 means of which excavated material may be raised with a skip along an inclined plane and may be, when raised sufficiently high, dumped into a chute through which it will be discharged preferably into a wagon or 25 truck for hauling away.

It is a further object of this invention to accomplish this by making use of the mechanism of one of a number of the more common forms of tractors.

30 I accomplish these objects as will be more fully hereinafter set forth in the drawings, specification and claims.

In the drawings:

Fig. 1 is a side elevation of my device as 35 applied to one of the well known forms of these tractors now on the market but having a portion of the extreme lower end of the loading incline broken away and also having the snubbing posts for the cables 40 omitted.

Fig. 2 is an end elevation of the same mechanism.

Referring now to the drawings in which the various parts are indicated by numerals, 2 and 3 are the rear wheels of the tractor. 4 is the rear axle, and 5 the housing covering an ordinary type of differential, the detail of which is not shown since such detail is not a part of this invention 45 and since it is the purpose to purchase a tractor containing this mechanism in the open market. 6 and 7 are winding drums attached respectively to the wheels 2 and 3 and rotating therewith and 8 and 9 are 50 brakes adapted to check the rotation of the drums 6 and 7 respectively. 11 and 12 are

posts or supports forming a frame and bolted to the axle 4 adjacent the drum 6 and 7 by means of U bolts 13 or any other suitable fastening means. 14 are jacks resting on 60 blocks 15 which jacks are shown simply as a means for raising the rear wheels of the tractor clear of the ground in order that they may freely rotate. 16 is the shaft bolted to the upper end of the posts 12 by 65 some means such as the clamps 17 and the screws or bolts 18 and bolted to the post 11 somewhat below the upper end thereof in a similar manner.

From this shaft inclined guides or runways 19 extend downward and forward over the front end of the tractor until the lower ends rest on the surface of the ground.

20 is a hopper attached to the post 11 and the runway 19 by simply bolting it thereto 70 and also supported from the said post and one of the runways, by means of the chains 21. The space between the runways is provided with a floor 22 which extends from the ground upward to the top of the hopper 20.

23 is a skip having a closed bottom and rear end and open top and front end which skip is provided with a bail 24 to which is attached a hoisting rope 25 which passes 80 over a pulley 26 journalled on the shaft 16 and thence passes around the drum 6 on which it is shown in the views herewith.

27 is a dumping and return cable which while shown stretched, is merely taut and 90 is not supposed to be under strain. This cable passes over a pulley 28 journalled on a shaft 29 at the upper end of the posts 11 and from this pulley 28 it passes around a pulley 30 by which its alignment is changed 95 thence to a second pulley 31 which brings it in alignment with the drum 7 around which it is adapted to be coiled. The outer end of the cable 27 is attached to a stake or some form of snubbing device which is not 100 shown in these drawings, which stake if it were shown in these drawings, would be at the point where the dotted position 27^A of the cable extended would hit the ground. Inasmuch however, as this is a variable 105 point and may be moved closer to, or further away from the machine as occasion may require, it is not material that this be shown.

At the back end of the skip 23 is an extension 32 in which are bolted pulleys 33 and 110 34 the cable 27 passing over the pulley 33 and under the pulley 34.

To use the device the machine is set up as shown in Fig. 1 and the rear wheels are raised clear of the ground by means of jacks 14 or any other suitable means which 5 may be therefor provided. One end of the cable 25 is fastened to the drum 6 and similarly one end of the cable 27 is fastened to the drum 7. The free end of the cable 27 is then carried forward some 25 or 30 feet 10 in front of the machine and securely staked to the ground and the machine is ready for use. The engine of the tractor is started with the differential out of gear as is usual. The brake 8 is then clamped against the 15 drum 6 and the differential thrown into gear. This will cause the free drum 7 to rotate and will draw the cable taut raising it to the position 27^a shown dotted. The differential is then thrown out of gear, the 20 brake 9 clamped to hold the cable taut in its dotted position 27^a and the drum 6 released. In the meantime the skip will have been raised to a position similar to the dotted position 23^a in which position it is 25 suspended by the roller in its dotted position 34^a and the cable 25 being on a loose drum will unwind, allowing the skip to run along the cable in its dotted position 27^a, until the skip strikes the ground. The brake 30 9 is then released so that the cable 27 again becomes a loose cable. The brake 9 is then clamped against the drum 7 and the differential thrown into gear. The cable 25 winds on the drum 6 dragging the skip 23 35 forward along the ground, causing it to pick up such loose material as lies in its path or such material as it may dig into.

When the skip reaches the foot of the inclined guides 19, it slides upward along the 40 floor 22 thereof until it comes to a position over the chute 20, at which point the brake 9 is released and the brake 8 clamped against its drum 6. The drum 7 will then wind the cable 27 thereon drawing it into the position 27^a and the skip 23 into the dumping 45 position 23^a.

When the cable 27 reaches the dotted position 27^a, the differential is thrown out of gear and the brake 9 clamped against the 50 drum 7. By this time the skip should be entirely empty, the brake 8 is then released so that the skip may travel along the dotted position 27^a of the cable to a position to pick up another load, after which the cycle 55 just recited, is repeated until such loading or digging as may be feasible or desired is accomplished.

Thereafter, should it be deemed desirable, the jacks 14 may be lowered until the wheels 60 2 rest on the ground and without disconnecting the cables the machine may be backed up a limited distance such as ten or fifteen feet, the jacks are again set in place, and the rear wheels raised off the ground. 65 The loading and dumping cycle may then be

repeated and the moving up again repeated until the limit of length of the cables be reached, when the snubbing posts must be loosened and the end of the cable 27 thus freed, be moved closer and again fastened. 70 When this machine is used as a loader, the material is dumped through the chute 20 into the bed 35 of a wagon or truck which may be placed under the chute for that purpose. 75

Should the machine be used for excavating a ditch, the dirt may similarly be hauled off or it may be dumped in piles under the mouth of the chute as may be desired.

It will of course be understood that the 80 details of construction here shown and described may be varied as may be found advisable without departing in any way from the spirit of my invention. The machine may be braced in such manner as may be 85 advisable, but as braces are merely details of construction, it is not thought advisable to include them.

Having fully described my invention, what I claim and desire to secure by Letters Patent of the United States is:—

1. In an excavator and loader, the combination with a tractor having a rear axle, rear wheels, a differential therefor and operating means, of a drum fastened to each of the rear wheels and rotating therewith, a frame fastened to the rear axle and extending upward therefrom, an inclined runway extending downwardly and forwardly from the upper end of said frame to the ground, a hopper beneath said runway, supported by said runway and said frame and extending laterally outward therefrom, an excavating skip, a pulley rotatably supported by said frame at the upper end of said runway, a loading and hoisting cable attached to the front of said skip and extending therefrom over said pulley and downward to and attached to one of said drums, return pulleys mounted on the rear end of said skip, a second pulley rotatably mounted on the upper end of said frame, a dumping and return cable having a suitable anchorage, and extending from said anchorage over said second pulley and thence to the other of said drums, and a brake for each of the said drums. 105

2. In an excavator and loader, the combination with a tractor having a rear axle, rear wheels, a differential therefor and operating means, of a drum fastened to each of the rear wheels and rotating therewith, a frame fastened to the rear axle and extending upward therefrom, an inclined runway extending downwardly and forwardly from the upper end of said frame to the ground, a hopper beneath said runway, supported by said runway and said frame and extending laterally outward therefrom, an excavating skip, a pulley rotatably sup- 110 115 120 125

- ported by said frame at the upper end of said runway, a loading and hoisting cable attached to said skip and extending therefrom over said pulley and downward to 5 and attached to one of said drums, return pulleys mounted on the rear end of said skip, a second pulley rotatably mounted on the upper end of said frame, a dumping and return cable having a suitable anchorage 10 and extending above said hoisting cable from said anchorage over said second pulley and thence over pulleys changing the alignment of said cable, to the other of said drums, a brake for each of the said drums, 15 and means for raising said rear wheels to permit free rotation thereof.
3. In an excavator and loader, the combination with a tractor having a rear axle, rear wheels, a differential therefor and 20 operating means, of a drum fastened to each of the rear wheels and rotating therewith, a frame fastened to the rear axle and extending upward therefrom, an inclined runway extending downwardly and forwardly from the upper end of said frame to the ground, an excavating skip, a pulley 25 rotatably supported by said frame at the upper end of said runway, a loading and hoisting cable attached to said skip and extending over said pulley and downward to and attached to one of said drums, return pulleys mounted on the rear end of 30 said skip, a second pulley rotatably mounted on the upper end of said frame, a dumping and return cable having a suitable anchorage 35 and extending from said anchorage over said second pulley and thence to the other of said drums, and a brake for each of the said drums.
4. In an excavator and loader, the combination with a tractor having a rear axle, rear wheels, a differential therefor, and operating means, of a drum fastened to 40 each of the said wheels and rotating therewith, a frame fastened to the rear axle and extending upward therefrom, an inclined runway extending downwardly and forwardly from the upper end of said frame to the ground, an excavating skip, a pulley 45 rotatably supported by said frame at the upper end of said runway, a loading and hoisting cable attached to said skip and extending over said pulley and downward to and attached to one of said drums, return pulleys mounted on the rear end of 50 said skip, a second pulley rotatably mounted on the upper end of said frame, a dumping and return cable having a suitable anchorage 55 and extending from said anchorage over said second pulley and thence to the other of said drums, and a brake for each of the said drums.

In testimony whereof I have hereunto set 70 my name.

ELDRIDGE P. DOUGLASS.
